(57) **CLAIM**

The ornamental design for a card game scoreboard, as shown and described.

DESCRIPTION

FIG. 1 is a isometric view of a card game scoreboard showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof showing my design.

The broken lines show portions of the card game scoreboard that form no part of the claimed design.
